UNITED STATES PATENT OFFICE.

SAMUEL L. BAILEY, OF NEW YORK, N. Y.

PORTABLE AND SECTIONAL FENCE.

SPECIFICATION forming part of Letters Patent No. 239,079, dated March 22, 1881.

Application filed December 18, 1880. (No model.)

To all whom it may concern:

Be it known that I, SAMUEL L. BAILEY, of New York city, in the county and State of New York, have invented certain Improvements in Portable and Sectional Fences, of which the following specification is a description.

This invention is in the nature of an improvement in portable fences; and the invention consists in making a fence of independent sections, connected together by means of dowel-pins and fastened to the ground by means of detachable posts, which are adapted to be driven into the ground and connected to the stationary parts of a section, all as hereinafter specified and claimed.

Figure 1 is an inner elevation of the first two sections of a fence made in accordance with my invention. Fig. 1* is a similar view of the, say, third section, showing the mode of joining it with the second and fourth or next adjacent sections. Fig. 2 is an edge elevation of the long post shown at the left in Fig. 1, and used for connecting two end sections. Figs. 3 and 4 are side elevations of the long and short posts.

Similar letters of reference indicate corresponding parts in all the figures.

A A designate the posts of a section of my improved fence, to which are attached an upper bar or rail, B, and a lower bar or rail, B'. 30 a a, &c., designate a series of panels, which extend from above the rail B to below the rail B', and are nailed or otherwise fastened to said rails. In the example of my invention shown in the drawings these panels are arranged so that they cross each other, forming diamond-shaped spaces, and several short panels are used at each end of a section. These panels may, however, be arranged vertically, if desired; or, instead of the panels, two or more 40 additional cross-rails may be used.

The posts A are intended to merely rest on the ground, or they may be slightly inserted therein. The rails B B' in the first section, 1, start flush with the face of the outer post, A, but extend over the inner post into ears d d', which are made with holes to receive pins p, to connect them with the perforated ears e e' of the rails B B' of the second section 2, these pins being secured in place by transverse lynchpins, if desired. The rails B B' of all the sections but the first and last are extended in

ears e e' at both ends, so that the sections may be connected by the pins p in perforations c in any number. The two end sections, if a simple inclosure is to be made, may be joined, as 55 in Fig. 2, by abutting them against a post, P, and running pins p' horizontally through the posts A P A', said post A' being shown as another way of finishing off an end-section post, it being only of a length equal to the distance 60 between the rails B B'. The fence is started from a post, P, driven into the ground, an end section being secured thereto by pins p', passed horizontally through holes c' in the section-posts, and c² in said posts P, and fastened by 65 cross-pins, if desired, and this section is joined to the next section, and it to the third, and so on, as heretofore described. The several intermediate sections are provided with the short posts P', having perforations c³, through which 70 and holes c⁴ in the posts A the pins p² are passed. The several sections are thus independently supported on and fastened to the ground, and are readily removed or replaced, as desired.

When it is desired to form an inclosure for temporary purposes the sections can be put together without using either the posts P or P'.

This fence combines all the advantages of a stationary fence with those of a portable fence. 80 The structure is simple, and it can be very easily put together and firmly set by any one, and can be as easily taken apart and packed away. It is light and compact, and can be readily transported from place to place, as may 85 be desired. It does not include any complicated mechanism, nor any iron cleats, bolts, latches, or stays to rust and get out of order, and as it is to be made of wood the cost of manufacture will be small.

I do not seek to claim, broadly, a portable fence, as I am aware that such structures are in common use.

I am further aware that a fence made in sections whose rails extend out into ears like mine 95 and are pinned together like mine to connect such sections is old; but such a fence has had also its meeting posts pinned together and a brace pinned to the section-post and jointed to a post that enters the ground at some distance 100 from the fence.

My invention does not employ the brace nor

posts inserted in the ground at a distance from the fence, nor does it pin the posts of adjacent sections together; but the posts are in line with the fence, and are themselves pinned to the section-posts, whereby great simplicity and compactness of parts are obtained.

What I claim as my invention, and desire to secure by Letters Patent, is—

A fence composed of the end and intermediate sections, 1 2, respectively, made up of the posts A and the rails B B', disposed as shown, and the panels a, combined with the end posts,

P, pinned to the face of the end section post, and the posts P', pinned to the posts A of the intermediate sections, all constructed and arranged as shown and described.

The foregoing description of my invention signed by me this 25th day of September, A.D. 1880.

SAMUEL L. BAILEY.
